LIFT KNOB FOR PLUMBING FIXTURE OR SIMILAR ARTICLE

Herbert V. Kohler, Kohler, Wis., assignor to Kohler Co.,
Kohler, Wis., a corporation of Wisconsin

Filed Jan. 9, 1959, Ser. No. 54,104

Term of patent 14 years

(Cl. D91—3)

Fig. 1

Fig. 2

Fig. 3

Fig. 1 is a perspective view of a lift knob for plumbing fixture or similar article showing my new design;

Fig. 2 is an elevational view of the same on an enlarged scale; and

Fig. 3 is a top plan view of the lift knob for plumbing fixture or similar article.

The dominant features of the design reside in the portions shown in full lines.

I claim:

The ornamental design for a lift knob for plumbing fixture or similar article, as shown and described.
